United States Patent Office

Des. 184,965
Patented Apr. 21, 1959

184,965

EYELASH-BRUSH

Murray Schotland, New York, N.Y.

Application October 22, 1957, Serial No. 48,202

Term of patent 3½ years

(Cl. D86—10)

FIG. 1

FIG. 2

FIG. 3

FIG. 4

Fig. 1 is a top plan view of an eyelash-brush, showing my new design;

Fig. 2 is a front elevational view thereof;

Fig. 3 is a side elevational view thereof;

Fig. 4 is a bottom plan view thereof.

I claim:

The ornamental design for an eyelash-brush, substantially as shown.
